UNITED STATES PATENT OFFICE.

PATRICK J. McALLISTER, OF COLUMBUS, OHIO, ASSIGNOR TO THE TOYSTOR COMPANY, OF CLEVELAND, OHIO, A CORPORATION OF OHIO.

DESIGN FOR A TOY STORE.

47,044.

Specification for Design.

Patented Mar. 2, 1915.

Application filed December 23, 1913. Serial No. 808,501. Term of patent 7 years.

To all whom it may concern:

Be it known that I, PATRICK J. McALLISTER, a citizen of the United States, residing at Columbus, in the county of Franklin and State of Ohio, have invented a new, original, and ornamental Design for Toy Stores, of which the following is a specification, reference being had to the accompanying drawing, forming part thereof.

Figure 1 is a side view, and Fig. 2 is an end view of a toy store, showing my new design.

I claim:

The ornamental design for a toy store, substantially as shown.

PATRICK J. McALLISTER.
